UNITED STATES PATENT OFFICE.

FRANK UNRUH, OF NEW ORLEANS, LOUISIANA.

PENCIL-SHARPENER.

1,074,026.

Specification of Letters Patent. Patented Sept. 23, 1913.

Application filed May 9, 1912. Serial No. 896,161.

To all whom it may concern:

Be it known that I, FRANK UNRUH, a citizen of the United States, residing at New Orleans, in the parish of Orleans and State 5 of Louisiana, have invented certain new and useful Improvements in Pencil-Sharpener, of which the following is a specification.

My invention relates to pencil sharpeners and has for its object the provision of a device 10 that is capable of being carried in the pocket and is also provided with means for securing the device to the pocket to prevent loss.

Another object of my invention is the 15 provision of a pencil sharpener having its blades capable of being adjusted to present new cutting edges for operation on the pencil as the cutting surface becomes dull.

Another object of my invention is the 20 provision of means for securing a pencil sharpener in the pocket having also clamping means to secure a pencil to said securing means.

My invention will be described in detail 25 hereinafter and illustrated in the accompanying drawings, in which,

Figure 1 is a top plan view of my improved pencil sharpener; Fig. 2, a side view in elevation; Fig. 3, an end view looking 30 toward the cutting blades; Fig. 4, a view of the opposite side of the pencil sharpener from that shown in Fig. 2; Fig. 5, a detail view of the blank from which the clamping member is constructed and Fig. 6, a detail view of the blank from which the cutting member is formed.

In the drawings, similar reference characters will be used to designate corresponding parts throughout the several views.

40 My improved pencil sharpener comprises a strip of steel or other suitable material indicated at 1 that is bent in its middle as shown at 2, and has its two sides formed by said bent portion inclined away from one another toward the free ends of the strip. The ends of the strip are then bent sharply as shown at 3 and extended on planes at substantially right angles to the sides of the strip and provided with inclined cutting 45 edges 4 that overlap one another as shown in Fig. 3. One of the ends of the strip is provided with an extended tongue on its lower portion shown at 5 that engages the lower portion of the other end of the strip 50 to act as a guide for said other end.

The strip 1 is as stated, formed of steel

or other suitable material capable of holding an edge and is also slightly resilient in nature so that the sides of the strip may be pressed inwardly toward one another as the 60 edges of the strip become worn where they cross to present new cutting surfaces for operation on the pencil. It will be understood, that in sharpening the pencil, the point of the pencil is drawn downwardly 65 and across the edges 4 and said edges serve to shave off the wooden portion of the pencil with the graphite contained therein. The device is likewise provided with a clamping member to hold the blades in adjusted positions as described, and this clamping member is formed of a blank as illustrated in Fig. 5 and will now be more particularly described.

The blank consists of a central plate 6 75 having laterally extending and integral tongues indicated at 7 and 8. Each of the tongues 7 and 8 is provided on one of its sides with tabs 9 and on its other side with two tabs 10 and 11, the tabs 10 being shorter 80 than said tabs 11, and all of said tabs being integral with said tongues.

The blank 6 is formed with outwardly curved extensions 12 at the end farthest removed from the tongues 7 and 8, and 13 85 and 14 indicate incisions made into the plate 6 and curved inwardly and toward one another as shown to form leaves 15, attached to said plate at the points 16, that are substantially elliptical in shape as shown. 90 These leaves 15 in forming the complete structure as shown in Figs. 1, 2, 3 and 4 are bent outwardly of said plate and toward one another to form the pencil clips as shown in Figs. 1, 3 and 4, and the points indicated at 95 17 and 18 at the two sides of the leaves 15 are bent slightly in the opposite direction from the direction of bending the leaves in forming the pencil clips, and when the device is bent as shown in Fig. 1 at 19 to form 100 the clamping member for the edge of the pocket, these points project inwardly so that they are in position to engage the material of the garment and hold the device from accidental removal.

The device for inclosing the sharpening blade is formed by bending the tongues 7 and 8 away from the plate 6 as shown at 20, and then toward one another at the point between the tabs 10 and 11. The tongues are 110 then bent outwardly away from the sharpening blade and secured together by means

of rivets or other suitable fastening means indicated at 21, and the free terminals of said tongues then curved away from one another as shown at 22 to provide a clamping device to receive a pencil or the like. The tabs 11 when the clamping member is in place on the pencil sharpener heretofore described, engage the outer surface of one of the sides of the strip of steel, while the tabs 9 and 10 are bent inwardly of the pencil sharpener and engage the inner surface of said strip of steel to hold the strip of steel securely clamped.

When the device is assembled as shown in Figs. 1, 2, 3 and 4, it will be apparent that it may be carried in the pocket, the tongue formed by the downwardly bent portion and the plate 6 forming a clip to secure the device on the upper edge of the pocket, the clamping members formed by the outwardly bent portions 22 on the free terminals of the tongues 7 and 8 and the leaves 15 operating as pencil clips to retain the pencils in place and prevent loss.

When the device is used as a pencil sharpener, it will be apparent that it is held between the thumb and fingers of one hand, while the pencil is being sharpened as heretofore described, and that the clamping member formed from the blank shown in Fig. 5 and consisting of the plate 6 and tongues 7 and 8 that encircle the strip of

metal may be used to move the two blades 4 toward one another to provide a new wearing surface as the blades become dull 35 at their intersection.

Having thus described my invention, what I claim is:—

1. In a pencil sharpener, a strip of steel bent on itself and having its sides inclined 40 slightly from one another, the terminals of said strip of steel then bent to overlap one another and provided with cutting surfaces, said cutting surfaces being converging and a clamping member inclosing said bent strip 45 of steel and slidably mounted thereon.

2. In a pencil sharpener, a strip of steel bent on itself and having its sides inclined slightly from one another, the terminals of said strip of steel then bent to overlap one 50 another and provided with cutting surfaces, said cutting surfaces converging, a clamping member comprising a plate bent on itself to form a pocket clip, and tongues integral with said plate and bent to inclose 55 said strip of metal and slidably mounted thereon.

In testimony whereof I affix my signature in presence of two witnesses.

FRANK UNRUH.
